UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

1,018,639.

Specification of Letters Patent.

Patented Feb. 27, 1912.

Application filed November 17, 1909. Serial No. 528,462.

To all whom it may concern:

Be it known that I, HERBERT H. STEELE, citizen of the United States, and resident of Marcellus, in the county of Onondaga and State of New York, have invented certain new and useful improvements in Type-Writing Machines, of which the following is a specification.

My invention especially relates to means for duplicating copies of typewritten matter and its object, generally stated, is to provide improved devices of the class specified.

To the above and other ends, my invention consists in the features of construction, combinations of devices and arrangements of parts hereinafter described and particularly pointed out in the claims.

In carrying out my invention in the present instance I provide a supporting frame 20 which is mounted on the carriage of the machine and carries two delivery rolls, a receiving roll and a roll of duplicating material such as carbon paper. The paper or work sheets from the two delivery rolls and from 25 the carbon roll is fed around the platen, the carbon between the two work sheets, the outermost sheet receiving impressions from the usual ribbon of the machine, which impressions are duplicated through the carbon 30 on the inner work sheet. After passing the printing line the two work sheets are separately controlled, the outer sheet being guided to a severing device by which said sheet may be severed at convenient intervals, 35 while the inner sheet is wound on the receiving roll automatically by devices which in the present instance are operated by a weight. A return feeding mechanism for the carbon paper is also provided, said 40 mechanism being operated by gravity, so that when certain of the paper controlling devices are released the carbon sheet is automatically returned, enabling the working field thereof to be repeatedly used until substantially exhausted.

My invention will be more particularly described in connection with the accompanying drawings, wherein—

Figure 1 is a transverse vertical sectional view of the upper part of a Monarch type-writing machine embodying my invention. Fig. 2 is a front elevation of the same, omitting some of the elements shown in Fig. 1. Fig. 3 is a longitudinal, sectional view of the

receiving roll, and showing also certain connections to said roll. Fig. 4 is a fragmentary plan view, partly in section, showing the left-hand end portion of the receiving roll and connections. Fig. 5 is a fragmentary end view of the receiving roll and associate parts. Fig. 6 is a transverse, sectional view of the platen and carriage to illustrate more especially the releasing means for certain of the paper feeding and controlling devices.

Although my invention is shown as applied to a Monarch typewriter, it is to be understood that it may be adapted in whole or in part to other styles of writing machines.

In Figs. 1 and 2 the top plate 1 of the machine is shown as supporting standards 2 to which are secured oppositely grooved track-ways 3, said track-ways coöperating with anti-friction balls 4 which provide 75 bearings for a slide bar 5, said slide bar being comprised in a platen carrier or carriage which further includes end bars 6 projecting forward from the slide bar and supporting a platen 7. The platen is provided with line 80 spacing devices which include a ratchet wheel 8 connected to one end of the platen and coöperating with a pawl 9 which is adapted to be operated through known devices by a line spacing arm or finger piece 10. 85 It will also be understood that the usual or suitable printing instrumentalities, inking ribbon and ribbon feeding and controlling devices are also to be employed although not shown in the drawings.

As shown in Figs. 1 and 6, lugs 11 extend forward from the slide bar 5 and pivotally support at 12 and 13 spring-pressed arms 14 and 15 arranged in pairs, the pair of arms 14 carrying the main feed roller 16 and the pair of arms 15 carrying the secondary feed roller 17. The main feed roller coöperates with the platen at the rear thereof while the secondary feed roller is arranged forward of the main feed roller at the under side of 100 the platen. Above and forward of the secondary feed roller is a spring-pressed scale plate 18 which extends lengthwise of the platen below the printing line and is pivotally supported at 19 on arms 20 which are 105 secured to the slide bar 5. A curved spring-pressed paper deflector or apron 21 is arranged at the rear and under sides of

the platen, being provided with openings through which the sections of the feed rollers protrude to engage the platen. Said deflector is supported on a rock shaft 22 which carries lugs 23, said lugs coöperating with lugs 24 on the arms 14 to swing said arms on their pivots and release the feed rollers and the scale plate. To effect the release of the secondary feed rollers, the arms 14 act 10 against the arms 15 to swing the latter downward, the lowering of said arms also relaxing the spring pressure against the deflector 21. To release the scale plate 18 one of the arms 14 acts against a lever 25, which 15 lever operates on an arm 26 projecting rearward from the scale plate, the result being that the scale plate is swung on its pivot 19 away from the platen to the position shown in Fig. 6. The releasing devices for the 20 scale plate are more fully set forth in the patent to George A. Seib, No. 912,186, granted February 9th, 1909. To turn the rock shaft 22 to release the paper feeding devices, means are preferably employed such as are 25 disclosed in the pending application of Edwin E. Barney, Serial No. 403,531, filed November 23rd, 1907. Said means include a crank arm 27 fixed to one end of the rock shaft and pivotally connected at 28 with an 30 arm 29 terminating in a finger piece 30, said arm being pivotally connected at 31 with an arm 32 which is pivoted on the adjacent end bar 6. The normal positions of the releasing means and of the paper feeding and controlling devices thus far described are 35 disclosed in Fig. 1. When the finger piece 30 is pulled forward to the Fig. 6 position, it rocks the shaft 22 and moves the paper feeding devices to the released or inoperative 40 position shown in said Fig. 6. The arms 29 and 32 constitute toggle elements which are straightened when the finger piece 30 is pulled forward and which operate to hold the parts locked in released position. Other 45 paper controlling devices are provided which are especially adapted to the character of work for which my present improvements were primarily designed. Said devices include pressure rolls 33 which coöperate with 50 the platen above the printing line, each pressure roll being mounted on an arm 34 which is pivotally supported on a bar or rod 35 which may be the usual paper finger rod, said rod being arranged above the platen and somewhat to the rear of the axis thereof and being supported on the end bars 6 to which it is detachably secured by screws 35*. The rolls 33 are spring-pressed toward the 55 platen as presently explained and are intended to coöperate with the margins of a wide or record sheet, and I provide curved guide fingers 36 which are adapted to control the side margins of narrower sheets, used for writing bills in the present instance. 60 These paper fingers are accordingly ar- ranged each nearer the middle of the platen than its associate pressure roll 33. The paper fingers 36 are secured by rivets or otherwise to the inwardly off-set end portions 37 of arms 38, said arms having upturned ears 38a which embrace the associate arms 34 and are pivoted thereto at 39. A coiled spring 40 is arranged between each pair of ears and is partly housed in a cavity in the arm 38, said spring pressing the paper finger toward the platen. The paper fingers extend downward, overlying the scale plate 18 at their lower ends, while their upper end portions are curved forward as indicated at 36a for purposes presently to be 65 described. It will be apparent that when the paper releasing mechanism is operated by the finger piece 30 the upper end of the scale plate 18 swinging forward will operate against the lower ends of the paper fingers 36 and will swing said paper fingers away from the platen so as to release from said fingers any paper which may underlie them. It will further be apparent that this release of the paper fingers 36 will not affect the pressure rolls 33.

The paper supply devices in the present instance are mounted on a supporting frame which comprises two side plates 41, each of which has an inwardly projecting hub 42 which bears on the rod 35. The plates 41 are connected by tie rods 43 and extend rearward over the carriage bearing, the lower rear portions of said plates being connected by a cross bar 44 which is adjustably secured by screws 45 to the end plates and carries a bearing roller 46. The roller 46 bears on a bar or track-way 47 which is secured by screws 48 to lugs 2a integral with the standards 2. The supporting frame 105 may be held from movement relative to the platen carriage as by set screws 49 threaded through the hubs or collars 42 and engaging the rod 35. It will be understood that during movements of the carriage to and fro over the top plate, the supporting frame will move along with the carriage, the roller 46 running along the fixed track 47. The supporting frame is held in place by the rod or bar 35 which may be readily detached 110 from the platen carrier so that the supporting frame and the parts it carries may be readily and quickly removed or detached. The supporting frame carries two delivery roll holders 50 and 51 arranged one above 115 the other and a receiving roll holder 52, the construction of the latter being fully illustrated in Fig. 3. The roll holder 52 is mounted on a shaft 53 having a flattened side 54 and said roll holder comprises 120 flanges 55 and 56 having bosses 57 and 58 through which the shaft 53 passes, said bosses having openings corresponding with the flattened shaft so that the shaft and the flanges will turn together. Tubes or core 125

130

pieces 59 and 60 are fixed respectively to the hubs 57 and 58. The core piece 60 extends the full distance between the flanges while the core piece 59 is much shorter and fits within the core piece 60 at one end, frictionally engaging said core piece 60. The latter may be provided with a longitudinal slot 61 to receive the loose end of the associate roll of paper. The shaft 53 is adapted to turn in round bearing openings in the side plates 41. The left-hand end of the shaft carries a pinion 62 which is connected with devices presently to be described for transmitting motion to the shaft and from it to the roll holder 52. The right-hand end of the shaft is reduced and threaded to receive a thumb nut 63. The pinion 62 and thumb nut 63 prevent accidental displacement of the shaft and roll holder.

20 The shafts 64 and 65 which respectively support the roll holders 50 and 51 are similar to the shaft 53 except that they are not flattened, there being no necessity of transmitting movement from these shafts to their 25 roll holders 50 and 51 which may turn freely on their shafts when the work sheets carried by said roll holders are unwound. In lieu of the pinion at the left end of the shaft 53 each of the shafts 64 and 65 is provided at 30 its left-hand end with an enlargement, or head 66. The right-hand end of each of the shafts 64 and 65 carries a thumb nut 67. The roll holders proper 51 and 50 carry rolls of material or work sheets 68 and 69 and 35 are constructed like the roll holder 52 which has already been described. The roll holder 50 delivers the record sheet 69 which is comparatively wide, to the roll holder 52; and the flanges of the roll holder 50 are close to 40 the inner faces of the side plates 41. The roll holder 51 supplies the bill sheet 68 which is narrower than the record sheet, so that the roll holder 51 does not occupy the full length of its supporting shaft 64 between the plates 41. In order to prevent 45 endwise movement of the roll holder 51 on its shaft, spacing sleeves 70 are arranged on said shaft, one between each flange of the roll holder 51 and the adjacent side plate 41.

50 Forward of the shaft 64 a shaft 71 is supported in the side plates 41, said shaft carrying a roll holder for carbon paper comprising a core 72 and flanges 73 (Fig. 1). This roll holder is of the same length as the 55 roll holder 51 and accordingly spacing sleeves 74 may be arranged on the shaft 71 at the ends of the carbon roll holder (Fig. 2). The shaft 71 terminates at its left end in a head 75 which abuts the outer face of 60 the left-hand side plate 41. The right-hand end of the shaft 71 is reduced and threaded as indicated at 71^a to receive a thumb nut 76. The threading is continued along the reduced portion 71^a well within the right-hand 65 side plate 41 so that when the thumb nut 76

is tightened it will operate through the sleeves 74 to bind or clamp the carbon roll holder frictionally to the side plates 41 and prevent rotation of said roll holder.

As shown in Fig. 1 the free-end of the 70 carbon paper 77 is drawn down over the top and at the rear of the roll and is led over a metal roller 78, the ends of which are reduced as indicated at 79 and are adapted to bear in upwardly and rearwardly inclined 75 slot-ways 80 formed in the side plates 41, said slot-ways terminating at their upper ends in enlargements 81 through which the roller 78 may be removed. The roller 78 is adapted to act as a gravity device to draw 80 back the carbon paper after it has been fed forward for writing purposes and also to draw a fresh supply of paper from the carbon roll holder when the nut 76 is loosened. Preferably pinions 82 are secured to the reduced end portions 79 outside the side plates 41 and these pinions co-operate with rack sections 83 secured to the outer faces of the side plates and extending lengthwise of the slot 80. The racks and pinions 85 co-operate to prevent skewing of the gravity roller 78 and cause it to move uniformly up and down in the slot-ways. The carbon paper 77 passes under and around the gravity roller and thence is led upward and 90 over a flanged wooden guide roller 84 which is arranged above the top of the slot-ways 80 and slightly to the rear thereof, said guide roller being mounted on a shaft 85 which is supported on the side plates 41. 100 The carbon paper 77 passes over and around said guide roller and thence down over the usual paper table 86 to the main feed roller 16 around the platen and between the same and paper feeding devices hereinbefore described, the free end of said carbon paper terminating normally slightly above the printing line at the front of the platen. It will be understood that the side margins of the carbon paper at the front of the platen 110 are controlled by the paper fingers 36 but that said side margins are not engaged by the pressure rolls 33, the distance between said pressure rolls being greater than the width of the carbon sheet as well as of the outer work sheet 68. The unwound portion of said work sheet 68 is led forward and downward from the top of its roll, passing over the paper table 86 between the same and the carbon paper 77 and thence around 115 the platen between it and the main secondary feed rollers and paper guide fingers 36, being guided upward and forward over the forwardly curved ends 36^a of said paper fingers, to a curved guide or receiving plate 87. The curved plate 87 covers or houses the roll holder 52 at the front, said guide plate being provided at its ends with radial arms 88, these arms each terminating in a hub or center 89 which is perforated to permit of 120

the passage of the shaft 53. As shown in Fig. 3 the hub portions 89 are arranged between the side plates 41 and the adjacent flanges of the roll holder 52. To prevent the guide plate 87 from dropping down it is provided at its hub portions with laterally extending pins 90 which, as best shown in Fig. 5, engage slots or recesses 91 formed in forwardly projecting portions of the side plates 41. These slots 91 coöperate with the pins 90 to maintain the guide plate in normal position; but when the shaft 53 is withdrawn from its bearings the guide plate may be readily removed. Embracing the guide plate is a knife or cutter bar 92, the angularly disposed end portions 93 whereof are perforated at their inner ends to provide openings for the shaft 53. The left-hand side portion 93 engages the shaft 53 between the pinion 62 and the left-hand side plate 41, while the right-hand side portion 93 engages said shaft between the thumb nut 63 and the right-hand side plate 41. The knife or cutter bar is frictionally controlled near its bearings by the side plates 41 and may be swung to and set in any predetermined position circumferentially of the guide plate 87 by a finger piece 94 so as to vary the distance from the printing point 30 at which the sheet 68 may be severed. This enables the bar to be readily moved to the proper place for cutting a work sheet which is divided at regular intervals by perforating marks or otherwise. The limits of movement of the cutter bar 92 are indicated by the dotted line positions of said cutter bar shown in Fig. 1 near the upper and lower ends of the guide plate 87, said limits being determined by stop pins 95 extending laterally outward from the left-hand side plate 41 (Fig. 5) and being adapted to be engaged by the left-hand side portion or arm 93. The work sheet 68 passes up over the front of the guide plate 87 and between the same and the cutter bar 92, which bar serves to maintain the loose end of the work sheet against the guide plate. The portion of the work sheet 68 above the cutter bar may be severed when desired by pulling forward against the sharpened upper edge of the cutter bar 92.

The unwound portion of the work sheet or record sheet 69 is drawn forward over the top of its roll and down and around a wooden guide roller 96 which is arranged near the upper front corners of the side plates 41 and is mounted on a rod or shaft 97 supported on said side plates. From the guide roller 96 the work sheet 69 extends downward and rearward between the carbon roll holder and the receiving roller and passes behind a guide roller 98 and thence downward around the platen and between said platen and the carbon sheet 77. At the front of the machine and above the printing

point the side margins of the sheets 69 are engaged and controlled by the pressure rolls 33, which rolls are constantly urged toward the platen by coiled springs 99. One end of each spring is hooked around a lateral pin 100 on the adjacent side plate 41 while the other end is secured to a pin 101 fixed to and extending up from the associate arm 34. From the pressure rolls 33 the work sheet 69 passes upward to the receiving roll holder and behind and over the top of the core thereof, the loose end of said work sheet engaging in the slot 61 in the core piece 60. Preferably the receiving roll holder tends constantly to turn to wind the work sheet 69 thereon so that as the writing proceeds and the work is line spaced the written portion of the work sheet 69 is drawn upward automatically and wound on the receiving roll holder. The automatic means for turning said roll holder in the present instance comprises devices which are connected with the pinion 62 on the left-hand end of the shaft 53. As best shown in Figs. 3, 4 and 5 said devices include a gear wheel 102 which meshes with the pinion 62, said gear wheel being mounted on a shaft 103, the inner end whereof is reduced and bears in an opening in the adjacent side plate 41 while the outer end takes bearing 95 in a bracket 104 which is suitably secured as by screws 105 to the left-hand side plate 41 and curves outward and forward therefrom as shown in Fig. 4. The outer end portion 103^a of the shaft 103 projects beyond the supporting bracket 104 and is squared to coöperate with a detachable key (not shown) which may be applied to said shaft for winding purposes as hereinafter explained. Supported on the shaft between the bracket arm 104 and the gear 102 is a spool or drum 106 which is secured to the shaft as by a cross pin 107 so that the spool and shaft will always turn together. That periphery of the flange of said spool which is contiguous to the gear wheel 102 is formed with ratchet teeth 108, thus providing a ratchet wheel integral with the spool. Coöoperative with the ratchet wheel is a pawl 109 which is pivoted at 110 to the gear wheel 102 and is constantly pressed into engagement with the ratchet wheel by a leaf spring 111 which is secured to the gear wheel 102 by a screw 112. The construction is such that when the spool is turned in the direction of the arrow in Fig. 5 the ratchet wheel 108 will coöperate with the pawl 109 to force the gear wheel 102 to turn also and rotary motion will be transmitted from said gear wheel to the pinion 62 and thence to the shaft 53 and receiving roll holder 52. Rotary motion of the drum 106 in the opposite direction will not affect the gear wheel 102 and the receiving roll holder. The drum 106 is constantly urged to turn in

the direction of the arrow in Fig. 5 by a weight 113 (Fig. 1), said weight being carried by a pulley wheel 114 suspended from a cord 115, one end of which is secured to a hook 116 depending from a fixed support 117. At the opposite side of the pulley 114 from the hook or anchor 116 the cord passes over an idler wheel 118 which is pivoted at 119 to a bracket 120 secured to the support 117, the cord 115 passing downward from the front of the wheel 118 to the drum 106. It will be understood that the weight 113 falls as the receiving roll holder is turned to wind on it the work sheet 69. From time to time thereafter it will be necessary to turn the drum 106 backward, winding the cord 115 thereon and lifting the weight 113. This backward turning of the drum is accomplished preferably by applying a key to the squared end 103^a of the shaft 103 and turning said shaft backward or in a direction opposite to the arrow in Fig. 5. During the backward movement of the drum the ratchet teeth 108 will slide from under the pawl 109 and will not affect the gear wheel 102.

Assuming that normally the parts are in the relationship shown in Fig. 1, it will be understood that as the writing takes place the type impressions will be produced on the outer sheet 68 which may be a bill or invoice sheet through the usual ribbon (not shown) and will be reproduced on the face of the inner or record sheet 69 through the carbon paper 77. To space between the lines of writing the platen will be turned by operating the line spacing finger piece 19, thereby advancing the three sheets 68, 77 and 69 simultaneously. As the work sheet 69 is advanced the slack will be taken up by the receiving roll holder 52. The work sheet 68 as it advances will pass upward over the guide plate 87 and above the cutter bar 92, while the carbon sheet 77 will follow the work sheet 68. It will be recalled that the carbon roll holder is normally held clamped from rotation. Consequently as the carbon sheet is advanced during line spacing movements the gravity roller 78 will be lifted, traversing the slots 80. When the entries comprising a bill have been completed or when the end of a written bill passes above the top of the cutter bar 92 or at any other convenient time, the written portion of the bill sheet 68 above the cutter bar may be severed. Thereafter or when desired, the finger piece 30 may be pulled forward. The latter operation releases the outer sheet 68 and the carbon sheet 77 but does not release the record sheet 69 which will be held by the pressure rolls 33. As soon as the carbon paper is released the gravity roller 78 will fall to the bottom of the slots 80, thereby retracting the carbon paper over the platen and around the guide roller 84 until said carbon paper is restored

to normal position with its free end slightly above the printing line. It will be understood that by means of the gravity restoring devices the same portion of the carbon paper may be repeatedly used to reproduce the type impressions on the underlying work sheet.

When the carbon paper becomes so nearly exhausted that impressions from it would be too faint, the used end portion of the carbon paper may be severed and a fresh portion brought into use. This operation may be conveniently accomplished as follows: When the writing on any bill has been completed and the exhausted portion of the carbon is above the printing point and while the gravity roller is raised some distance in its guide slots, then without releasing the paper feeding devices the thumb nut 76 may be loosened, permitting the gravity roller 78 to run down to normal position. As the gravity roller runs down it will unwind a fresh portion of carbon paper on the carbon holder, which will turn, of course, during such unwinding movement. After the gravity roller reaches normal position the carbon roll holder may again be locked by tightening the thumb nut 76. After the next bill is printed and prior to releasing the paper feeding devices the used portion of the carbon paper may be torn off against the cutter bar 92 along with the bill sheet 68. It will be understood that thereafter when the finger piece 30 is pulled forward releasing the carbon paper the latter will be drawn backward by the gravity roller 78 until the top of the new writing portion of said carbon paper lies just above the printing line. When the carbon paper has been exhausted from its roll holder and a carbon roll holder containing a fresh supply is to be substituted, the gravity roller 78 should first be removed by lifting it to the top of its slotways and withdrawing it through the enlargements 81. After the new carbon roll holder has been put in place, the end of the carbon paper is drawn around the platen to a point above the printing line and is held by the feed rollers. Then the gravity roller 78 is replaced and allowed to drop in its slots, drawing a corresponding amount of carbon paper from the supply roll.

It will be apparent that when in the course of the work the paper on any delivery roll holder is completely exhausted, then a fresh roll may readily be arranged in place, it being only necessary to unscrew the thumb nut associated with said roll holder and then to remove the supporting shaft, after which the roll holder may be slipped out and the frictionally held parts separated so that the longer core piece may receive the fresh roll of paper. It will also be apparent that from time to time as the receiving roll holder is filled, it may be dismounted

in the same way and the roll of written records removed. Said roll may, of course, be divided into suitable lengths and kept in book form in loose leaf binders so that it will be convenient for reference purposes.

It may be stated that the present construction was more particularly designed for the typewriting of cash tickets and a simultaneous record thereof. These tickets are uniform printed blanks, so that the roll or web 68 comprises a large number of such tickets connected end to end. In other words the strip 68 is printed at regular recurring intervals with the same blank form. Each ticket indicates a separate transaction and may comprise one or a dozen typewritten entries; or if the transactions are greater than the space allowed on a single ticket, the items may be continued on the next succeeding ticket without filling in the blanks in the printed form at the head of said succeeding ticket. These tickets are in the nature of bank check invoices that are sent out daily to correspondents. The duplicate entries on the record roll 52 are not used except for reference when there arises some question of error so that it is of advantage to condense the records of the roll 52 as much as possible. Therefore, after the last entry is made on any ticket, instead of turning the platen to the first line position on the next succeeding ticket the platen may be line spaced one space, and the feed rollers released to allow the carbon paper to be automatically fed backward. Then the sheet 68 is drawn forward to the position for writing the first line on the next ticket after which the feed rollers are restored to their normal positions. The result of this mode of operation is that the record roll presents a continuous column of entries in condensed form, although there may be blank spaces of varying lengths between the entries on successive cash tickets.

Of course the devices herein disclosed may be employed in any other way that is found desirable in connection with matter to be typewritten.

It will be noted that by my present invention I provide a platen carriage comprising a removable bar, or paper finger rod in the present instance, which is arranged over the platen and extends lengthwise thereof, in combination with a detachable supporting frame comprising side plates bearing on said bar and a transverse bar connecting said side plates, said transverse bar carrying a wheel which runs on a fixed track-way, said supporting frame supporting roll holders which are arranged between the side plates; that said roll holders are mounted on shafts, said shafts being journaled on said side plates; that said roll holders comprise a delivery roll holder for a transfer medium such as carbon paper and a receiving roll holder;

that in the present instance said receiving roll holder receives one of the written work sheets; that said receiving roll holder is adapted to be turned automatically by gravity-operated means; that said gravity-operated means comprises a weight and a cord; that said cord is connected with said receiving roll holder by means comprising intermeshing gear wheels and a connected drum; that said drum is connected with one of said intermeshing gear wheels by a pawl and ratchet mechanism; that the rotary device or receiving roll holder last referred to is adapted to be turned in one direction by automatic means which include a gravity-operated element; that hand controlled means are adapted to move said element against the force of gravity and independently of said rotary device; that the automatic means includes a gravity operated shaft; that manual means are adapted to turn said shaft in the opposite direction to gravity independently of said rotary device; that a rotary holder for material adapted to be fed over the platen is provided, said rotary holder comprising flanges having hubs and tubular core pieces fixed to said hubs, one core piece fitting inside the other; that a supporting shaft for said holder has a flattened portion which cooperates with openings in said hubs, said openings each having a straight side engaging the flattened portion of said shaft; that means are provided for feeding a plurality of sheets of material over a platen in combination with a rotary holder for certain of said sheets and a curved guide for certain other of said sheets, said guide partly housing said holder; that said guide is stationary and is concentric with said holder and detachably mounted on a frame which supports said holder; that said guide in the present instance is a curved plate having angularly disposed parallel arms engaging a shaft on which said holder is mounted; that said curved plate has pin and slot connections with the supporting frame for said holder; that a severing device is concentric with said guide or curved plate; that said severing device as herein shown is a cutter bar which is adjustable to desired positions around said curved guide or plate; that in combination with a platen are provided a pressure roll carrier and a spring-pressed guide finger pivoted to said carrier; that a pressure roll has a bearing on an inwardly extending portion offset from a spring-pressed arm which is pivoted on a bearing arranged lengthwise of a platen; that a second spring-pressed arm is pivoted to said first named arm, said second arm also having an inwardly off-set portion to which is secured a curved guide finger; that the off-set portion of one arm is longer than the off-set portion of the other so that the guide finger

and the pressure roll are in different planes; that pairs of guide fingers and pairs of rolls are provided, the rolls being further apart than the guide fingers, the guide fingers being adapted to coöperate with narrow sheets which pass between the rolls without being engaged thereby; that in combination with a platen means are provided independent of the platen for feeding material relatively to the platen, which material is fixed or fast at one end; that in the present instance the means last referred to is gravity operated; that it acts to feed material independently of the platen which is fast at one end at a point away from the platen; that releasable material feeding means is provided in combination with the platen, together with means for back feeding material when said releasable means are released, the end of said material which is away from or, in the present instance, above the platen, being secured or fast so that it does not move when the other parts of it are being fed backward over the platen; that the back feeding means above referred to are in the present instance operated by gravity; that the gravity-operated means in the present instance comprises a roller which may be of metal or other material which is of suitable weight; that rack and pinion devices are provided to coöperate with the ends of a gravity roller to control the same; that a roll holder is provided for material which is adapted to be fed over a platen by releasable means; that a clamp is adapted to clamp or fix said roll holder; that means are provided for feeding the material last referred to while said platen and said roll holder are quiescent or motionless; that devices are provided for feeding material relatively to the platen while the roll holder which carries said material is clamped or otherwise held fast or fixed; that said devices are operative also to turn said roll holder to unwind the material therefrom; that prior to so turning said roll holder the latter must of course be unclamped or released; that means are provided for feeding material while the holder thereof is inoperative, being held from operation by clamping means; that a single automatically operated means is provided whereby a sheet of material may be moved endwise, as distinguished from a sidewise movement longitudinal of the platen, this endwise movement taking place in either direction, that is, forward or backward, at the will of the operator and according as one end portion or the other of the sheet of material is held from movement, separately controlled means being provided for coöoperating with the opposite end portions of the material to hold it as described; that said separately controlled means comprise in the present instance on one hand a releasable feed roller coöoperative with the platen and on the other hand a rotary material carrying roll holder or carbon roll which may be clamped to hold it from rotation; that means for holding fast the end of said material opposite to the feeding means are associated with automatically operated means for feeding at pleasure from either end of a sheet of material; that a gravity operated device is adapted to feed at pleasure from either end of a sheet of material; that two rolls over which material is fed are combined with a single means for feeding material away from either of said rolls at pleasure; that two rolls between which material in sheet form is arranged are combined with a gravity operated device arranged between said rolls and means for causing said device to operate at will to feed material away from either roll at pleasure without affecting the relationship between said material and the other roll; that independently operated sets of devices are provided for releasing material from a platen and for releasing a clamped roll holder which supplies said material to the platen, said sets being combined with means operating automatically to feed the material when either of said sets is operated; that there is provided a combination of a roll holder, means for holding the same fixed, a platen, means for holding against the platen the material supplied by said roll holder, a guide roller between said platen and said roll holder, and a gravity-operated feeding device coöoperative with said material between said guide roller and said roll holder; that a gravity-operated device is adapted to feed material in opposite directions; and that a gravity-operated device is provided for feeding material backward and forward, said device being movable independently of the material which it is adapted to feed.

Various changes may be made without departing from my invention.

What I claim as new and desire to secure by Letters Patent, is:—

1. In a typewriting machine, the combination of a platen carriage comprising a bar arranged over the platen and lengthwise of the same, a detachable supporting frame comprising side plates bearing on said bar, and a transverse bar connecting said side plates, a wheel on said transverse bar, a fixed track for said wheel, and roll holders arranged between said side plates and supported thereon.
2. In a typewriting machine, the combination of a platen carriage comprising a bar arranged lengthwise of the platen and above the same, a detachable supporting frame comprising side plates bearing on said bar, tie rods connecting said side plates, and a transverse bar connecting said side plates at the rear, a roller on said bar, a fixed track

- way for said roller, a plurality of shafts journaled on said side plates, and roll holders mounted on said shafts.
3. In a typewriting machine, the combination of a platen carriage comprising end bars, and a bar supported on said end bars and arranged above the platen, a detachable supporting frame comprising side plates having collars bearing on said bar, tie rods 10 connecting said side plates, a cross bar carried by said side plates, a roller on said cross bar, a fixed track-way for said roller, a pair of delivery roll holders mounted on said side plates, a carbon paper roll holder mounted on said side plates, and a receiving roll holder mounted on said side plates.
4. In a typewriting machine, the combination of a platen, a rotary device for receiving material fed from said platen, 20 means for automatically turning said device in one direction including a gravity operated element, and hand controlled means for moving said element against the force of gravity and independently of said rotary device.
5. In a typewriting machine, the combination of a platen, a rotary device for receiving material fed from said platen, means for automatically turning said device 30 including a gravity operated shaft, and manual means for turning said shaft in the opposite direction independently of said rotary device.
6. In a typewriting machine, the combination of a platen, means for feeding a plurality of sheets of material over said platen, a rotary holder for certain of said sheets, and a curved guide for certain other of said sheets, said guide partly housing said 40 holder.
7. In a typewriting machine, the combination of a platen, means for feeding a plurality of sheets of material over said platen, a rotary holder for certain of said sheets, a 45 supporting frame for said holder, and a guide for certain other of said sheets, said guide being concentric with said holder and detachably mounted on said supporting frame.
- 50 8. In a typewriting machine, the combination of a platen, means for feeding a plurality of sheets of material over said platen, a rotary holder for certain of said sheets, a shaft for said holder, and a curved plate for guiding certain other of said sheets, said plate having angularly disposed parallel arms engaging said shaft.
9. In a typewriting machine, the combination of a platen; means for feeding a plurality of sheets of material over said platen; a rotary holder for certain of said sheets; a 60 shaft for said holder; a curved plate for guiding certain other of said sheets, said plate having angularly disposed parallel arms engaging said shaft; and a frame which provides a support for said shaft, said curved plate having pin and slot connections with said frame.
10. In a typewriting machine, the combination of a platen; means for feeding a plurality of sheets of material over said platen; a rotary holder for certain of said sheets; a curved guide for certain other of said sheets, 70 said guide partly housing said holder; and a severing device concentric with said guide. 75
11. In a typewriting machine, the combination of a platen; means for feeding a plurality of sheets of material over said platen; a rotary holder for certain of said sheets; a curved guide for certain other of said sheets, 80 said guide partly housing said holder; and a cutter bar adjustable along said curved guide.
12. In a typewriting machine, the combination of a platen; means for feeding material over said platen; a curved guide plate 85 for guiding said material after it leaves the platen; and a cutter bar adjustable to desired positions around said guide plate.
13. In a front-strike typewriting machine, 90 the combination of a platen; a bar arranged lengthwise of the platen; a spring pressed arm pivoted on said bar and provided with an integral inwardly extending off-set portion; a pressure roll having its 95 bearing in said off-set portion; a second spring pressed arm pivoted to said first named arm and having an inwardly off-set portion; and a curved guide finger secured to said second arm. 100
14. In a typewriting machine, the combination of a platen and guiding devices comprising two pivotally mounted arms, one pivoted on the other and each having an inwardly off-set portion, one off-set portion 105 being longer than the other, one of said off-set portions carrying a pressure roll and the other a curved guide finger.
15. In a front-strike typewriting machine, 110 the combination of a platen; a bar arranged above the same; a pair of inwardly off-set supports pivoted on said bar; springs controlling said supports; pressure rolls pivoted on the off-sets of said supports and adapted to coöperate with wide sheets; arms having inwardly off-set portions and pivoted on said supports; springs for said last named arms; and guide fingers mounted on said last named arms and coöperating with narrow sheets. 115
16. In a front-strike typewriting machine, 120 the combination of a platen; feed rollers at the under side thereof; a scale plate arranged lengthwise of said platen below the printing line; means for releasing said feed rollers and moving said scale plate away from the platen; and spring pressed guide fingers releasable by said scale plate. 125
17. In a front-strike typewriting machine, 130 the combination of a platen; feed rollers at

- the under side thereof; a scale plate arranged lengthwise of said platen below the printing line; means for releasing said feed rollers and moving said scale plate away from the platen; arms carrying pressure rolls which rolls coöperate with the platen above the printing line; and guide fingers pivoted on said arms and releasable by said scale plate independently of said pressure rolls. 5
18. In a front-strike typewriting machine, the combination of a platen; feed rollers at the under side thereof; a scale plate extending lengthwise of the platen below the printing line; guide fingers extending transversely of the printing line and having outwardly curved portions at their upper ends; and a curved guide plate arranged above and forward of the curved portions of said 10 guide fingers.
19. In a typewriting machine, the combination of a platen; and means independent of the platen for feeding material relatively thereto, said material being held from movement at one end as it is fed. 25
20. In a typewriting machine, the combination of a platen, and gravity operated means for feeding material over the platen independently thereof, the material being held from movement at one end as it is fed. 30
21. In a typewriting machine, the combination of a platen, releasable means coöperative with the platen for feeding material thereover, the end of the material away from the platen being held from movement, and means for back feeding said material when said 35 releasable means are released.
22. In a typewriting machine, the combination of a platen; releasable means coöperative with the platen for feeding material thereover, the end of the material away from the platen being held from movement; and gravity operated means for feeding said material back over the platen when said 40 releasable means are released.
23. In a typewriting machine, the combination of a platen; releasable means coöperative with the platen for feeding material thereover in one direction, the end of the 45 material away from the platen being held from movement; and means for retracting said material in the opposite direction independently of the platen when said releasable means are released. 50
24. In a typewriting machine, the combination of a platen; releasable means coöperative with the platen for feeding material thereover in one direction, the end of the material away from the platen being held from movement; and a gravity roller for 55 retracting said material in the opposite direction independently of the platen when said releasable means are released. 60
25. In a typewriting machine, the combination of a platen, a gravity roller for mov- 65
- ing endwise material over the platen independently thereof, one end of said material being held from movement, and rack and pinion devices controlling said roller. 70
26. In a typewriting machine, the combination of a platen; releasable means for moving endwise material over said platen; a roll holder for said material; a clamp for said roll holder; and means for moving endwise said material while said platen and 75 said roll holder are quiescent.
27. In a typewriting machine, the combination of a platen; a roll holder for material adapted to be fed over said platen; a clamp for said roll holder; and devices for feeding 80 said material relatively to said platen while said roll holder is clamped.
28. In a typewriting machine, the combination of a platen; a roll holder for material adapted to be fed over said platen; a clamp 85 for said roll holder; and devices for feeding said material relatively to said platen while said roll holder is clamped, said devices being operative also to turn said roll holder to unwind said material therefrom. 90
29. In a typewriting machine, the combination of a rotary platen; a rotary roll holder for material adapted to be fed over said platen; holding means for maintaining said material against said platen; means for 95 clamping said roll holder; and means for moving endwise said material while said holding means is inoperative and said clamping means is operative.
30. In a typewriting machine, the combination of a rotary platen; a rotary roll holder for material adapted to be fed over said platen; holding means for maintaining said material against said platen; means for 100 clamping said roll holder; and means for moving endwise said material while said holding means is inoperative and said clamping means is operative, said last named means also operating when said clamping means is inoperative and said holding means 105 110
31. In a typewriting machine, the combination of a platen, and paper feeding devices comprising an automatically operating device for moving a sheet of material endwise, said device acting at will to move opposite end portions of said sheet, the change of direction in the movement of the sheet being effected independently of the connection between said sheet and said automatically operating device. 115
32. In a typewriting machine, the combination of a platen, paper feeding devices comprising an automatically operating device for moving a sheet of material endwise, and separately controlled means for holding opposite end portions of said material from movement. 120
33. In a typewriting machine, the combination of a platen, and paper feeding de- 125 130

vices comprising an automatically operating gravity controlled roll for moving a sheet of material endwise, said roll acting at will to move opposite end portions of said sheet.

34. Paper feeding mechanism for typewriting machines comprising two rolls over which paper is fed, and a device operative to move the paper endwise away from either of said rolls at will when the other roll is held from movement.

35. In a typewriting machine, the combination of two rolls between which material in sheet form is arranged, a gravity operated device between said rolls, and means for causing said device to operate at will to feed material away from either of said rolls at pleasure without affecting the relationship between said material and the other roll.

36. In a typewriting machine, the combination of a roll holder, means for holding the same fixed, a platen, means for holding against the platen the material supplied by said roll holder, independently operated sets of devices for releasing the material from said platen and for releasing said roll holder, and means operating automatically to move endwise said material when either of said sets of devices is operated.

37. In a typewriting machine, the combi-

nation of a roll holder, means for holding the same fixed, a platen, means for holding against the platen the material supplied by said roll holder, a guide roller between said platen and said roll holder, and a gravity operated feeding device co-operative with said material between said guide roller and said roll holder.

38. In a typewriting machine, material moving means comprising a gravity-operated device for moving endwise material in opposite directions at pleasure, the change of direction in the movement of the material being effected independently of the connection between said material and said gravity-operated device.

39. In a typewriting machine, material moving means comprising a gravity-operated device for moving material endwise, said device acting directly on said material and being movable independently of said material.

Signed at Syracuse, in the county of Onondaga and State of New York this 15th day of November, A. D. 1909.

HERBERT H. STEELE.
